UNITED STATES PATENT OFFICE.

THOMAS WEBSTER, OF NEW YORK, N. Y.

SHIPPING-BOX FOR EGGS AND OTHER FRAGILE ARTICLES.

1,193,323.

Specification of Letters Patent.

Patented Aug. 1, 1916.

Application filed November 16, 1914. Serial No. 872,385.

To all whom it may concern:

Be it known that I, THOMAS WEBSTER, a citizen of the United States, and a resident of New York, in the borough of Brooklyn, 5 county of Kings, and State of New York, have invented certain new and useful Improvements in Shipping-Boxes for Eggs and other Fragile Articles, of which the following is a specification.

10 This invention relates to boxes for shipping eggs, glassware and other fragile articles by parcel post, express or otherwise.

15 The object of the invention is to provide a shipping box of this character possessing the qualities of lightness in weight, cheapness of construction and sufficiency of strength, combined with a shock absorbing yieldability which protects the contents 20 against breakage and insures safety thereof in transit, and the parts thereof may be easily and readily assembled.

25 With the above and other objects in view, the invention will be best understood when having reference to the accompanying drawing, in which,

30 Figure 1 is a perspective view of the shipping crate, embodying my invention; Fig. 2 is a vertical transverse section taken 35 on line 2—2 of Fig. 3; Fig. 3 is a vertical longitudinal section taken on the line 3—3 of Fig. 2; Fig. 4 is a plan view of a foldable blank adapted to form one of the interior holding members for the articles to be carried 40 within the box. Fig. 5 is a plan view of said blank in set-up position, the end flaps thereof being shown in locked position at one end and in released position at the other end. Fig. 6 is an end view of the 45 locked end of the set-up blank shown in Fig. 5. Fig. 7 is a transverse vertical section taken on line 7—7 of Fig. 5.

50 Similar reference numerals indicate corresponding parts throughout the various figures of the drawings.

55 The shipping box in the particular embodiment herein shown is rectangular in form and designed to carry eggs, but the invention is not restricted to such form nor such articles. This embodiment comprises an outer inclosing casing, box or crate 10 having a cover 11 and a plurality of interior shock absorbing article holders 20—21 and 22—23 for the fragile articles. The outer casing 10 which may be constructed

of any suitable material is preferably made of pasteboard, stiff paper, fiberoid or the like. The cover 11 of suitable material is preferably hinged integrally or otherwise on the line 12 to the side wall 15, and provided with downward overlapping flaps 13 and 14.

Two holders for eggs or other articles are disposed side by side in the casing 10, each holder being composed of two elastic 60 or yielding members or supports disposed one above the other, the eggs or other articles being carried between them. One of these holders is composed of a flexible, collapsible lower member 20 and a similar flexible, collapsible upper member 21, the member 21 being disposed in inverted position over the member 20. The other holder is composed of a similar lower foldable member 22 and a corresponding inverted upper 65 folding member 23. Each holder is preferably adapted to carry a plurality of eggs or other articles to be packed and transported.

70 In the manufacture of the interior holders, the members thereof, whether upper or lower, are stamped as shown in Fig. 4 from one continuous blank of cardboard or similar material 4. This blank comprises a rectangular top 24 and longitudinal side walls or flaps 35 and 36 integral therewith and separated from the opposite edges thereof by longitudinal scores or creases 60 and 61 respectively. The top 24 is provided with a series of transverse openings forming supporting skeleton pockets 25 disposed in a 75 row apart from one another as shown in Fig. 4. Each pocket 25 is adapted to receive one end of an egg or other article to be contained, said pocket being somewhat smaller than the diameter of such article at its 80 largest part and being preferably elliptical in shape to increase its adaptability to eggs of different sizes. The pockets may be of different shapes according to the articles to be suspended therein. The central portion 85 24 having the skeleton pockets 25 is provided with a score or crease 26 which is disposed about midway between and runs parallel with the side flaps aforesaid and on a line intersecting said pockets about the center thereof. This central portion is provided at one end with two end flaps 27 and 28 disposed side by side and separated from said portion by a transverse score 62 and from each other by a longitudinal cut or 90 100

105

110

severance 63, and at its opposite end with similar end flaps 29 and 30 separated therefrom by a transverse score 64 and from each other by a longitudinal cut 65. Both sets of said end flaps have their outer side edges 33 beveled and their outer ends 34 beveled as shown in Fig. 4. The side flap 35 has end closing flaps 37 and 39 at its opposite ends separated from said side flaps by transverse scores 75 and 76 and the side flap 36 has end closing flaps 38 and 40 separated from its opposite ends by transverse scores 77 and 78. These scores preferably break joint with and are outside the plane of the transverse scores 62 and 64 so as to permit the end flaps which are attached to the side flaps to fold inside the end flaps which are attached to the central body portion. The end flap 37 has a V-shaped notch 41 on its inner edge and the end flap 38 has a similar notch 41' on its outer edge. Similar notches 41² and 41³ are located at the inner and outer edges respectively of the end flaps 39 and 40.

In setting up and assembling the holders within the casing two blanks like that shown in Fig. 4 are used for each holder, four being required for the box shown in Fig. 2. Each of these blanks is folded as follows: The side flaps 35 and 36 are folded along the scores 60 and 61 at right angles to the body or central portion 24. The end flaps 27 and 28 continuous with said body portion are folded downward along the transverse score 62 and the end flaps 29 and 30 also continuous with said body portion are likewise folded downward along the transverse score 64. The end flaps 37 and 38, which are continuous with the side flaps 35 and 36, are folded inward on the transverse scores 75 and 76 and interlocked by means of their notches 41 and 41'. The end flaps 39 and 40, which are also continuous with the side flaps 35 and 36, are folded inward along the transverse scores 77 and 78 and interlocked by means of their notches 41² and 41³. The top 24 is bent downward along the score 26 thereof forming a shallow V-shaped depression. This downward bending of said body swings the end flaps 27 and 28 outward and brings their beveled edges 33 against the side walls 35 and 36 and brings the beveled ends 34 flush with the bottom of the casing. Two of the blanks thus folded are set up side by side in the box 10, forming the lower members 20 and 22 respectively of the two holders contained in said box. The eggs 50 or other articles to be packed are placed with their lower ends in the pockets 25 of said lower members. The other two blanks thus folded and constituting the upper members 21 and 23 of said holders are disposed in inverted position over the members 20 and 22 and their pockets engage the upper ends of said eggs or other articles.

35 The V-shaped bends or folds along the

bodies of each member of each holder, intersecting the pockets thereof, cause the holder to have contact with the eggs or other articles on oppositely inclined planes transversely thereof. The crease 26 acts as a hinge along the line of pockets and imparts a resiliency to the angular bend in which the pockets are located. As thus constructed the body of the holders rise and fall easily under the flexibility imparted by the crease 26 and spread and contract laterally under shocks or jars to which the box may be subjected. Such resiliency is under control by the end flaps 27 and 28 and 29 and 30 in connection with the side walls, and the articles are prevented from bumping against the top or bottom of the box.

The device has given excellent results in practical use for transmitting frail articles by parcel post.

85

In the accompanying drawings, I have shown the simple and preferred form of the invention, but it is to be understood that I do not limit the same to the embodiment shown, but reserve the right to make any changes or alterations that come within the spirit of the invention, and defined in the appended claims.

Having thus described my invention, I claim as new and desire to secure by Letters 95 Patent:—

1. A shock absorbing holder for eggs or other fragile articles, comprising a blank having supporting side walls and a top integral therewith and provided with transverse openings constituting skeleton pockets and a longitudinal score along said top intersecting said transverse openings and permitting said pocketed top to rise and fall and laterally spread and contract under shock, and means for limiting such movement.

100

2. A shock absorbing holder for eggs or other fragile articles, comprising a blank having supporting side flaps and a central body portion provided with a skeleton pocket and a folding crease intersecting said pocket and forming a hinge along which said body portion bends freely, rising and falling and laterally spreading and contracting under shock, and end flaps having beveled edges adapted to engage said side walls and limit such movements.

110

3. A shock absorbing holder comprising two members disposed in inverted relation and holding an article between them, each member having a central body portion and supporting side flaps integral therewith, said central body portion having a skeleton pocket and a folding crease intersecting said pocket and forming a hinge along which said body portion bends freely, rising and falling under shock, and means for limiting such movement.

120

4. A blank for a container consisting of

125

a flexible sheet comprising a top having a series of transverse openings forming skeleton pockets disposed apart from one another along said top and with a longitudinal score intersecting said pockets between the ends thereof, said score permitting said top to bend and form an angular bulge at the sides of said pockets in setting up for use.

5. In a device of the class described, comprising a body portion, a longitudinally extending crease formed therein, dividing the body portion into sections, side-walls formed with the body portion, end flaps formed with the side-walls, having locking-
10 means for holding the side walls in an operative position, and for including the sections of the body portion, end flaps formed with the body portion for limiting the movement of the sections of the body portion, said
15 body portion having elongated openings formed therein, and a like body portion arranged inverted above the first-named body portion, with the openings of the second body portion in substantial registration

with the openings of the first-named body portion.

6. A blank for an article carrier consisting of a flexible sheet provided with parallel longitudinal scores constituting lines of fold between the body portion of the sheet designed to form a top and the portions thereof designed to form the side walls, scores between said top and the portions designed to form end flaps, said top having transverse openings forming skeleton pockets disposed apart from one another and a crease intersecting said pockets at the sides thereof, said crease permitting said body to bend and form an angular bulge along said pockets in setting up for use.

In testimony that I claim the foregoing as my invention, I have signed my name in presence of two subscribing witnesses.

THOMAS WEBSTER.
